APPARATUS FOR AUTOMATICALLY POSITIONING THE ROLLS IN ROLLER-MILLS IN ACCORDANCE WITH THE MATERIAL FEED

Fritz Tanner, St. Gallen, Switzerland, assignor to Gebruder Buhler, Uzwil, Switzerland

Application December 27, 1949, Serial No. 135,239

Claims priority, application Switzerland April 14, 1949

4 Claims. (Cl. 241—64)

1

My present invention relates to a starter and regulator for roller mills comprising pressure-fluid servomotors for automatically throwing the grinding rollers and feed rollers in and out of gear, and a device disposed in the goods inlet for controlling the pressure-fluid feed to the servomotors.

The starters and regulators of the type indicated, as known in the art of grinding grain and the like, do not operate quite satisfactorily and do not quite correspond to practical requirements owing to the fact that the grinding rollers are thrown in and out of gear at a comparatively slow speed.

While in the case of a manually operated starter, the latter is quickly thrown in by the miller through a good pull, and the grinding rollers through exerting a blow onto a pawl which locks the engaging lever are quickly released under spring pressure. The automatic throwing in and out of gear is slowed down through the use of a pressure-fluid servomotor.

The said disadvantage of known roller mill starters and regulators of the type indicated and further disadvantages which will become apparent to one skilled in the art from the following description of one known form of starter and regulator, are avoided by virtue of my present invention in that a reversing valve is provided in the pressure-fluid supply pipe of the servomotors, which valve is reversible through the controller in order to permit of quickly throwing the grinding rollers and the feed rollers in and out of gear.

The invention will be described in more detail in connection with the accompanying drawing wherein like characters of reference indicate identical elements, and wherein

Figs. 1 and 2 show two different forms of my present invention in vertical section applied to a known roller mill.

Fig. 3 is a diagrammatic view showing a number of units illustrated in more detail in Fig. 1, with connecting fluid pressure conduits shown therein; and

Fig. 4 is a diagrammatic view similar to that of Fig. 3, illustrating a number of units of Fig. 2.

Fig. 1 shows a known double roller mill in the casing 1 of which two pairs of grinding rollers 2, 3 and two pairs of feed rollers 4, 5 are disposed. The regulating mechanism for the movable grinding roller of each roller pair is disposed out-

side the casing 1 and laterally thereof. For the sake of clarity, the regulating mechanism associated with the right-hand mill side is shown in the drawing on the left-hand mill side. The said regulating mechanism comprises a swing bearing for the movable grinding roller 2, which bearing is engageable through a rod 7 provided with a handwheel 7'. The said rod is pivoted to an engaging lever 8 which is mounted on the coupling shaft 9. Numeral 10 designates the disengaging spring acting on the bearing 6. A servomotor piston 11 is operatively connected to the lever 8 and operates in a cylinder 12 fixed to casing 1. Numeral 13 designates a fixed abutment for lever 8. A hopper 14 for the goods to be ground is disposed above the feeding rollers 4 and 5 and is closable at the bottom through a feeder segment 15 disposed above the feeder roller 4. A lever 16 serves for actuating the segment 15 and is connected to the piston 18 of a second servomotor through a rod 17. The piston 18 operates in a cylinder 19 in which is disposed a spring 24 which acts on the piston 18 so that the latter tends to move the segment 15 to closing position. A pump 23 delivers pressure fluid through piping 25 into the cylinders 12 and 19. The fluid arriving in cylinder 19 tends to depress the piston 18 against the action of spring 24 and thus to open the segment 15. Such opening action, however, only takes place when the bore 18' in piston 18 is closed. When the bore 18' is open, the fluid can return through piston 18 to pump 23. A control pin 20 is provided for closing the bore 18' and has a tip 20' at the bottom, which cooperates with the said bore, while the pin at the top is pivoted to an arm 21 on which is disposed a controller 22 for the goods in hopper 14.

In Fig. 1, an auxiliary reversing slide valve is shown, which comprises a cylinder 26, a piston 27, a spring 28, and seven ports 29-35. The said valve for the sake of clarity is shown in a larger scale than the mill unit. The said valve, as regards its stroke and diameter, actually is substantially smaller than the piston 18 associated with feeder segment 15. The piston 27 has a relieved portion forming an annular chamber 36. The fluid delivered through the pump 23 flows through line 25 and a wide bore 33 into cylinder 26 and thence into the annular chamber 36 of piston 27. In the position shown, the fluid is dis-

charged through port 38 and flows into cylinder 12. The latter thus communicates directly through large-diameter lines with the pump or the central circulating system, and the pressure in cylinder 12 is exactly the same as throughout the system. The port 34, connecting the main line 25 with the pressure space of cylinder 26, is of very narrow bore. A further line 29, of somewhat larger bore, connects cylinder 26 with cylinder 19. The automatic regulating system operates in the following manner: When the roller mill is thrown into gear, the pump 23 supplies fluid into main line 25, under a pressure regulated by means of an overflow valve (not shown) provided between lines 25 and 35, from which valve the pressure fluid returns to the suction port of pump 23 through return line 35. The controller 22 and consequently the tip 28' of control pin 28 are retained in their upper position by the action of spring 22'. The upper end of bore 18' of piston 18 is fully open and the pressure fluid supplied from the main-line 25 to the branch line 34, 29 through the very narrow port 34 freely escapes through bore 18'. Thus the pressure in the branch line remains low. The spring 24 maintains piston 18 in its upper position and holds the segmental feed-gate 15 in closing position. Piston 27 is held by spring 23 in its lower terminal position. Port 38 of cylinder 26 is closed and port 31 opened, the main line 25 leading to the servomotor cylinder 12 thus being connected to the return line 35. The piston 11 of servomotor 12 is retained by action of spring 10 in its left terminal position and thus the grinding rollers 2, 3 are out of grinding engagement. As soon as goods are supplied to the roller-mill, the pin 28 is depressed by the goods running into hopper 14 and weighting the controller 22, whereby the bore 18' is closed by the tip 28'. The pressure fluid then depresses the piston 18 until a passage of such size is created between the tip 28' of pin 28 and the upper end of bore 18' that the fluid can escape through said bore. The pin 28 and piston 18 thus always are moved as if they were rigidly interconnected. The fluid pressure is defined by the strength of spring 24, the diameter of piston 18 and the position of tip 28', which latter depends on the quantity of goods supplied to the roller mill. Substantially at the same time at which the segmental feed gate 15 is opened, the piston 27 of the reversing slide valve 26 is pushed to its upper terminal position by the rising pressure below it, thus opening the pressure fluid main line 25 to the servomotor 12. The latter then suddenly moves the grinding roller 2 into grinding engagement with the roller 3, the servomotor 12 being connected through large-diameter lines with the pump 23.

The opening of the segmental feed gate 15 is continuously changed dependent upon the quantity of goods supplied to the roller mill, while the grinding rollers remain in engagement with each other. As supply of goods through the hopper 14 ceases the controller 22 permits the spring 22' to raise the controller, the lever 21 and the pin 28. The latter uncovers the upper end of bore 18' in piston 18, and like pressures are built up below piston 27 and above piston 18. The magnitude of this pressure here again is defined through the diameter of piston 18 and the spring 24. The said elements are so designed that the pressure suffices to compress the spring 28 of piston 27 and maintain the latter in the position shown. When, however, the pin 28 uncovers a part of bore 18' in piston 18, the fluid is discharged through said

bore at a quicker rate than at which it can be replenished through the narrow port 34. The space under piston 27 thus is depressurized, and spring 28 can depress piston 27 to its lowermost position. Communication between the ports 39 and 33 thus is interrupted, and communication established between port 31 and discharge port 35. The fluid thus may flow from cylinder 12 through large-bore lines to pump 23, and stopping is effected very quickly. The piston 27, which has a very small stroke only, never can stand still in an intermediate position, but always will occupy either of the terminal positions at once so that the ports 30 and 31 in cylinder 12 are always fully open.

In Figures 1 and 2, the piston valves 27 are provided with a stop 41 to form an annular channel around the same when the piston valve 27 is in its down position. In this lowermost position of the piston valve 27 pressure fluid can flow to the underside of the piston valve 27 from the restricted or smaller conduit 34 into the space below the piston slide valve 27, and building up pressure moves the piston valve 27 against the action of the spring 28, to its uppermost position, provided fluid is prevented by the valve 28' from flowing through the channel 18'.

Owing to the very narrow bore in port 34, the piston 18 of feeder segment 15 moves at a slower speed than when controlled only by the pin 28. Such slower speed, however, is not a disadvantage, but an advantage, since the goods, e. g. the light husk of the third and fourth groats, does not flow uniformly through the hopper 14 past the controller 22, but tends to stick or form bridges and then to give way suddenly. The piston 18 of the arrangement shown in Fig. 1 follows up such irregularity only slowly and equalizes the same so as to bias the position of feeder segment 15 inconsiderably and so as to maintain a uniform feed of the goods.

A further feature of the form of invention shown in Fig. 1 is that only a very small portion of the total pump delivery flows through the narrow port 34 so that the fluid consumption for the slow movements of piston 18 with feeder segment 15 is small, since piston 11 for the grinding rollers does not consume any pressure fluid when engaged.

Finally, the pressure in the cylinders 19 and 26, by suitably selecting the diameter of piston 18 and the spring 24, may be maintained at a lower value than in the pump piping 25 or in the central supply system, and the feeder segments 15 of all the mill units hooked up thus can operate independently of each other.

In Fig. 3, the respective reference characters are the same as in Figures 1 and 2 for the corresponding parts, except that a further line 39 from the cylinders 19 to the pump 23 is shown. This conduit 39 is merely an elongation of the conduit adjacent the cylinder 19 in Fig. 1, or an elongation of the conduit from the check valve 38 to the pump 23, in Figure 2.

In Figures 1 and 2, an overflow valve 40 is shown for taking care of any overflow pressure, the usual spring therein being correspondingly regulated.

While Fig. 3 diagrammatically shows a number of units illustrated in Fig. 1, the Fig. 4 is a similar diagrammatic illustration of a series of units shown in Fig. 2.

In the second form of my present invention shown in Fig. 2, the feeder segment 15 is not regulated through a servomotor 18, 19 but is moved

through a conventional feeding flap 14a in hopper 14 by means of levers 16 and 16a. A slight movement of said flap in its topmost position, i. e. when goods run no more, may be utilized for quickly starting and stopping the grinding and feeding rollers by means of the control slide valve. For such purpose the line 29 of the latter terminates in a small check valve 38 which in operation is closed through the pressure in line 29. When goods run no longer, i. e. when flap 14a is at the highest elevation, the valve 38 opens and the fluid can quickly flow from line 29 back to the pump, since fluid cannot flow so quickly through the very narrow port 34. The piston 27 thus is lowered and uncovers the large-bore port 31 through which the fluid then flows from the cylinder 12 into the return line 35. Piston 11 thus disengages quickly. When goods run again, the operation described is reversed.

By adding, in the form shown in Fig. 1, a stop valve 29a in the line 29 connecting reversing valve 26, 27 and regulator 18—20, the supply of fluid to the latter may be interrupted. When said valve 29a is closed, the pressurized fluid, e. g. compressed air, supplied through fine-bore port 34 pushes the piston 27 of the reversing slide valve upwardly, and the grinding and feeding rollers thus remain in gear, even though there is only a small quantity of goods left in hopper 14, i. e. when the regulator 18—20 would throw the rollers out of gear. It is, however, desirable in such case to let the rollers remain in gear in order that the hopper 14 may be completely emptied through the narrow gap between segment 15 and roller 4, which gap is always present.

When compressed air is used as fluid, all the return lines to the pump are eliminated. Figs. 1 and 2 for such case show the piping system for the reversing slide valve in dash-and-dot lines. When, further, connecting a narrow pressure line at 32, fresh compressed air also flows into the discharge line 35 when the reversing slide valve is disengaged, i. e. when piston 27 is fully depressed. In such latter case, not only the spent air from cylinder 12, which will flow through port 31, but also fresh air flowing through port 32 will be available for actuating a signal device 37. The latter will be heard as long as the piston 27 remains in its bottommost position, i. e. as long as the mill unit is inoperative. As soon as the unit is put in operation, the signal pipe 37 is silenced.

The rod 17 of piston 18 of the servomotor also may actuate the speed governing means (not shown) of the grinding and feeding rollers, besides the feeder segment 15.

When the controller 22 only performs the operation of throwing the grinding rollers and the feeding rollers in and out of gear, while the supply of goods (by means of segment 15) is regulated manually or mechanically, the piston 18 of the arrangement shown in Fig. 1 may be blocked in cylinder 19, the mode of operation of the reversing organs remaining the same.

In the two forms of invention described with reference to Figs. 1 and 2, a uniform and high pressure is maintained in the servomotors for starting and stopping the grinding and feeding, and in the supply pipes for the servomotors. In the servomotors for regulating the supply of goods, and in the pressure spaces of the reversing slide valve a lower pressure prevails. In the case of a central fluid supply to a plurality of parallel-operating mill units, the said lower pressure may be different for the various units in order to

attain a proper operation of the units when they encounter different resistances.

What I claim as new, and desire to secure by Letters Patent, is:

- 5 1. A system for regulating the grinding gap of a roll pair dependent upon the quantity of material fed thereto, having a pair of grinding rollers, adapted to be put into and out of grinding relation, a servomotor having a cylinder and a piston, means connecting said piston with at least one of said rollers, a spring interposed in said means, the tension of said spring being related to the diameter of said piston, a hopper having a wall, a material flow controller in said hopper, a pair of feed rollers in the said hopper, and in the path of said material flow from said hopper wall, and spaced from said wall one roller above the other, a feeder segment disposed between said hopper wall and said upper feed-roller, means connecting said feeder segment with said material controller, said means including fluid pressure operated means having a cylinder and a valve and a valve stem, said valve stem being movable by said fluid pressure and connected with said controller, a pump for said pressure fluid, and a conduit from said pump to said grinding roller operating servomotor for placing the grinding rollers into grinding position, and for supplying
- 10 20 the said valve cylinder with pressure fluid to operate said feeder segment to open the material flow to the feeder rolls, and thus to said grinding rollers, the combination of a slide valve mechanism interposed in said pump conduit leading from said pump to the grinding roller servomotor, said mechanism comprising a cylinder with conduit openings, a piston slide valve in said cylinder having a hollow interior and an outer circumferential groove, a spring in said valve interior having one end acting against said slide valve, and the other end against said cylinder, said slide valve being shorter than the interior length of said cylinder, the aforesaid pump conduit supplying fluid to said outer circumferential groove of said slide valve, when said valve is in one position, a conduit connecting with the space in said circumferential groove and with the conduit to said servomotor cylinder, and a restricted conduit supplying fluid to said slide valve cylinder outside of said piston slide valve, a conduit guiding said restricted fluid from said slide valve cylinder to the feeder segment cylinder of the aforesaid fluid pressure operated means, a conduit leading off from the pump conduit for supplying the slide valve cylinder with fluid when the slide valve is down, a conduit leading off from the servomotor conduit and to the upper part of the slide valve cylinder when said slide valve is down, and a conduit communicating with the interior of the slide valve cylinder and with the pump for returning the fluid returning from said servomotor to said pump, whereby the fluid from the pump unrestrictedly passes through the
- 15 30 40 45 50 55 60 65 70 75 groove in the slide valve to the servomotor to actuate the piston in the servomotor cylinder to place the grinding rollers in grinding relation, to obtain a fast grinding engagement, and the fluid return from said servomotor to the pump flows promptly through unrestricted conduits, enabling the spring at the servomotor to place the grinding roller to ungrinding relationship, the feed segment opening and closing its space in response to the amount of flow of the material, the restricted fluid flow below the said slide valve actuating

said feeder segment means to open and close said feeder segment in respect to said feeder rollers.

2. The structure of claim 1, in which the said fluid pressure operated means is a servomotor in which the piston has a channel from top to bottom of said piston and the valve stem is adapted to open or close said channel depending on the position of said material controller.

3. The structure of claim 1, in which the said fluid pressure operated means has its valve stem resting on a material controller in the form of a hinged plate, and a lever interposed between said plate and the said feeder segment.

4. The structure of claim 1, in which a plurality of such structures are adjacent each other having common conduits to and from said pump. 15
